UNITED STATES PATENT OFFICE.

ROBERT S. MENNIE, OF CHICAGO, ILLINOIS, ASSIGNOR TO FLANNERY BOLT COMPANY,
OF PITTSBURGH, PENNSYLVANIA.

STAYBOLT STRUCTURE.

1,395,286.

Specification of Letters Patent.

Patented Nov. 1, 1921.

Original application filed February 5, 1916, Serial No. 76,333. Divided and this application filed August 29, 1919. Serial No. 320,646.

To all whom it may concern:

Be it known that I, ROBERT S. MENNIE, a citizen of Canada, and a resident of Chicago, in the county of Cook and State of Illinois, 5 have invented certain new and useful Improvements in Staybolt Structures; and I do hereby declare the following to be a full, clear, and exact description of the invention, such as will enable others skilled in the art 10 to which it appertains to make and use the same.

This invention relates to improvements in staybolt structures, this application being a division of application for patent filed by me 15 on the 5th day of February, 1916, and designated by Serial Number 76,333.

The object of my present invention is to provide a flexible staybolt structure of the type embodying a sleeve or bushing in which 20 the head of the staybolt is mounted, which shall be simple in construction, which may be quickly and effectively installed, and in which a closure for the sleeve shall be integrally united to the latter and said sleeve 25 integrally united to the boiler sheet.

By integrally uniting as by welding very important defects in present practice are eliminated. Threaded sleeves and caps become leaky and must be removed eventually, 30 whereas a sleeve or cap integrally united eliminates leakage.

With this and other objects in view, the invention consists in certain novel features of construction and combinations of parts 35 as hereinafter set forth and pointed out in the claims.

In the accompanying drawings, Figure 1 is a sectional view of a staybolt structure showing one embodiment of my invention, 40 and Figs. 2, 3 and 4 are views of modifications.

1 represents the outer sheet of a boiler having an opening 2 which in the embodiment of the invention shown in Fig. 1 is of uniform diameter from the outer to the inner face of the sheet and therefore presents a straight wall.

A bearing sleeve 3 passes through the opening 2 and projects inwardly beyond the 50 inner face of the boiler sheet, said sleeve being (in the embodiment of the invention shown in Fig. 1) cylindrical in form having an external diameter which is uniform approximately from one end to the other. The

bore of the sleeve is made tapering and 55 curved throughout a portion of the sleeve and affords a seat or bearing for the rounded head 4 at the outer end of a staybolt 5. The bearing sleeve 3 is provided at its outer end with a shoulder or narrow annular 60 flange 6 which overlies the outer face of the boiler sheet and sustains such inward pull as may be exerted on the sleeve by the staybolt. The peripheral portion of the shoulder or annular flange 6 is integrally 65 united to the boiler sheet by means of a weld 7. The integral union effected between the sleeve and the boiler sheet not only rigidly secures the sleeve to the boiler sheet but it also serves to prevent leakage past said 70 sleeve.

A closure 9 is located within the outer end portion of the sleeve 3 over the bolt head and this closure is fixedly and integrally united to the sleeve by a weld 10 located within the 75 sleeve and around the edge portion of said closure. The closure thus seals the outer end of the sleeve and prevents leakage of any steam which might find its way past the bolt head. The bolt may be provided with 80 a tell-tale hole 11 which may extend from end to end of the bolt and closed in the headed end by a permanent plug 12.

In the form of the invention shown in Fig. 2, a conical bearing sleeve 13 is shown 85 passing through a conical opening 14 in the boiler sheet. In the construction shown in Fig. 2, the annular flange at the outer end of the sleeve is omitted, but the sleeve projects outwardly beyond the outer face 90 of the boiler sheet, as at 15, and is integrally united to the latter by a weld 16.

The construction shown in Fig. 3 is similar to that shown in Fig. 2, except that the closure for the sleeve is removable, being 95 made in the form of a plug 17 screwed into the outer end of the sleeve, and the construction shown in Fig. 4 is similar to that shown in Fig. 1 except that a plug 18 screwed into the outer end of the sleeve 100 constitutes a removable closure for the sleeve.

In all the forms of the invention, the sleeve is so mounted in the boiler sheet as to resist inward pull of the staybolt and 105 said sleeve projects beyond the outer face of the boiler sheet and is integrally united to the latter by welding.

Having fully described my invention what I claim as new and desire to secure by Letters-Patent, is:—

1. In a staybolt structure, the combination with a boiler sheet having an opening, of a bearing sleeve passing through said opening and extending inwardly beyond the same and prevented from inward movement by engagement with the boiler sheet, said sleeve also projecting beyond the outer face of the boiler sheet, a weld surrounding the outwardly projecting end of the sleeve and uniting said sleeve to the boiler sheet, a staybolt having a head mounted in said sleeve, and a closure in the sleeve over the bolt head.
2. In a staybolt structure, the combination with a boiler sheet having an opening, of a bearing sleeve passing through and inwardly beyond said boiler sheet and prevented from inward movement by engagement with the same, said sleeve also projecting outwardly beyond said sheet, a weld integrally uniting the outwardly projecting end of the sleeve to the boiler sheet, a closure within said sleeve, a weld integrally uniting said closure to the sleeve, and a staybolt having a head mounted in said sleeve.
3. In a staybolt structure, the combination with a boiler sheet having an opening, of a bearing sleeve passing through said opening and projecting inwardly beyond the same and provided at its outer end with a shoulder overlying the outer face of the boiler sheet, a weld integrally uniting the peripheral portion of said shoulder to the boiler sheet, a staybolt having a head mounted in said sleeve, and means closing the outer end of the sleeve over the bolt head.
4. In a staybolt structure, the combination with a boiler sheet having an opening, of a bearing sleeve passing through said opening and projecting inwardly beyond the same, said sleeve having a shoulder at its outer end overlying the outer face of the boiler sheet and welded to the latter, a staybolt having a head mounted in said sleeve, and a closure welded in the outer end of the sleeve.

In testimony whereof, I have signed this specification in the presence of two subscribing witnesses.

ROBERT S. MENNIE.
